CLAIM

The ornamental design for a light fixture, as shown and described.

DESCRIPTION

FIG. 1 is a front perspective view of a first embodiment of a light fixture showing my new design;

FIG. 2 is a right side elevation view thereof; the left side being a mirror image;

FIG. 3 is a back elevation view thereof;

FIG. 4 is a front elevation view thereof;

FIG. 5 is a top plan view thereof;

FIG. 6 is a front perspective view of second embodiment of a light fixture showing my new design;

FIG. 7 is a right side elevation view thereof; the left side being a mirror image;

FIG. 8 is a back elevation view thereof;

FIG. 9 is a front elevation view thereof;

FIG. 10 is a top plan view thereof;

FIG. 11 is a front perspective view of third embodiment of a light fixture showing my new design;

FIG. 12 is a right side elevation view thereof; the left side being a mirror image;

FIG. 13 is a back elevation view thereof;

FIG. 14 is a front elevation view thereof; and,

FIG. 15 is a top plan view thereof.

The broken lines in the drawings represent environmental subject matter and form no part of the claimed design. The bottom surface is unclaimed.
